OR D 12,048

Design No. 12,048, dated November 30, 1880.

UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 12,048, dated November 30, 1880.

Application filed July 31, 1880. Term of patent 3½ years.

To all whom it may concern:

Be it known that I, EDUARD LEISSNER, of the city of New York, in the county and State of New York, have invented a new and original Design for Wall-Paper, of which the following is a specification.

This invention relates to a new and original design for wall-paper and similar fabric.

It consists in the new arrangement and grouping of figures, hereinafter more fully described.

The accompanying photograph illustrates a face view of wall-paper having my new design.

This design is Egyptian in its effect, and shows a body or frieze, A, containing two main groups, B and C, and also shows a border, D.

The group B is composed of a bird-like figure, E, with head *a* and body *b*, covered with scale-like feathers, and with a circular ruff, *d*, behind the head. From the edges of this ruff *d d*, on either side, project wing-shaped figures *e e*, and from the body *b* project triangular feathers *f f f*, with fan-shaped ornaments upon them. A zigzag band, F F F, runs around the figure E at the top and sides. Along the bottom of the group B and of the design runs the band G, composed of poppy-like flowers *g g g*, standing upright and alternating with buds *h h h* of apparently the same flower. A vine, H, with leaves *i*, buds *j*, and bell-shaped flower *l*, runs between group B and group C over an ornamental background.

Group C consists of a parallelogram, I, set upon a square base, K, which last contains an ornament composed of alternate circular and oval figures radiating from a common center. The figure I is ornamented with figures *m m*, projecting upward from its sides and resembling the spade on playing-cards, and also with a center stripe, *n n n*, on which are found circular figures alternating with figures like the club in playing-cards, set in pairs, one projecting on each side of the strip *m m*. Into the parallelogram I, near its top, project the flowers *l l*.

The border D consists of the semi-rosette L, with a cross-shaped center, and feather-like projections radiating from it. On either side

of the figure L is a circular rosette, M, with a vine, *o*, surrounding it and connecting the figure L with the rosette M.

The group *q* consists of two cup-shaped flowers, *p p*, having between them a larger similar flower, *r*, which last contains a semi-rosette, *s*. Between the flowers *p p* stand the buds *t t*.

Two similar bands, P P, ornamented with a series of cup-like flowers alternating with small buds, edge this border horizontally.

I claim—

1. The design for wall-paper, consisting of the bird-like figure E, composed of figures *a b d e f*, substantially as shown.

2. The design for wall-paper, consisting of the group B, composed of figures E F *a b d e f*, substantially as shown.

3. The design for wall-paper, consisting of the figure G, composed of alternating poppy-like flowers *g g g* and buds *h h h*, substantially as shown.

4. The design for wall-paper, consisting of the vine-like figure H, with leaves *i*, bud *j*, and flower *l*, substantially as shown.

5. The design for wall-paper, consisting of the parallelogram I and inclosed ornamentation *m n*, substantially as shown.

6. The design for wall-paper, consisting of the group C, composed of parallelogram I, a rectangle, K, and their ornamentations, substantially as shown.

7. The design for wall-paper, consisting of the group B and group C, substantially as shown.

8. The design for wall-paper, consisting of the group B, vine H, and group C, substantially as shown.

9. The design for wall-paper, consisting of the groups B and G, substantially as shown.

10. The design for wall-paper, consisting of the groups B, G, and C, substantially as shown.

11. The design for wall-paper, consisting of the groups B, G, and C and figure H, substantially as shown.

12. The design for wall-paper, consisting of the figure L, forming a half-rosette, with cross in center and radiating projections, substantially as shown.

13. The design for wall-paper, consisting of the circular figure M, with surrounding vine o, substantially as shown.
14. The design for wall-paper, consisting of the group q, composed of cup-shaped flowers p p, similar flower r above and between them, and semi-rosette s, substantially as shown.
15. The design for wall-paper, consisting of the figure P, composed of alternate cup-like flowers and of buds, substantially as shown.
16. The design for wall-paper, consisting of the body or frieze A and border D, substantially as shown.
17. The design for wall-paper, consisting of the border composed of figures L M o P Q p r s t, substantially as shown.
18. The design for wall-paper, consisting of the figures E a b d e f F G g h H i j I m n K L M o P p r s t, substantially as shown.

Witnesses: EDUARD LEISSNER.

RUDOLF KLEEMANN,
WILLY G. E. SCHULTZ.
